UNITED STATES PATENT OFFICE.

GEORGE MELVIN HOLLEY, OF DETROIT, MICHIGAN.

CARBURETER.

1,171,200.

Specification of Letters Patent.

Patented Feb. 8, 1916.

Application filed June 14, 1909. Serial No. 502,023.

To all whom it may concern:

Be it known that I, GEORGE M. HOLLEY, a citizen of the United States, residing at Detroit, in the county of Wayne, State of Michigan, have invented certain new and useful Improvements in Carbureters; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to carbureters for internal combustion engines, and consists in the construction and arrangement of parts hereinafter more fully set forth and pointed out particularly in the claims.

The object of the invention is to provide simple and efficient means for feeding into the carbureting chamber a plurality of hydrocarbon fuels of varying density or specific gravity, enabling the operator to start the engine upon the lighter or more volatile fuel and then shift the carbureting device so as to feed the heavier fuel, the arrangement being such as to afford two independent fuel reservoirs which may be made to communicate independently with a single fuel nozzle which extends into the carbureting chamber, and to provide for regulating the flow of fuel from said reservoirs at will.

The above object is attained by the structure illustrated in the accompanying drawings, in which:

Figure 1 is a central vertical section through a carbureter involving my invention, the line of said section being indicated by dotted line 1—1 on Fig. 2. Fig. 2 is a top plan view of said carbureter with the cap or cover removed. Fig. 3 is an enlarged fragmentary view in section through the upper end of the fuel nozzle and the controlling valve therein, through the medium of which either of two carbureting fuels which the carbureter is adapted to supply, may be fed to the carbureting chamber.

Fig. 4 is a horizontal section as on line 4—4 of Fig. 3. Fig. 5 is a central vertical section, as on line 5—5 of Fig. 1. Fig. 6 is a horizontal section as on line 6—6 of Fig. 5, the dotted line in said figure showing the position of the handle of the controlling valve when the device is set to feed from one

of the fuel reservoirs. Fig. 7 is a view similar to Fig. 6, the dotted line indicating the position of the handle of the controlling valve when said valve is set to feed from the other of said reservoirs.

Referring to the characters of reference, 1 designates the body of the carbureter which is preferably cylindrical in form and which is divided by a transverse partition 2 into two independent fuel reservoirs indicated at 3 and 4, respectively. Each reservoir is provided with a valve chamber 5 communicating therewith, and in each of said valve chambers is a valve seat 6 surrounding an intake opening 7 which may be connected in any suitable manner with a source of fuel supply, not shown. In each of the valve chambers is a gravity valve 8 adapted to normally rest upon the valve seat 70 of the intake opening and prevent the passage of fuel therethrough. Engaging freely each of the gravity valves 8 is an arm 9 which is pivotally mounted at 10 in the passage connecting each valve chamber with its reservoir, the inner end of each of the arms 9 being secured to a semicircular float 11 located in each of the fuel reservoirs. The upper end 12 of each of the valves 8 is guided in a way 13 formed in the cap 14 75 which covers each of the valve chambers 5. By this arrangement the fuel in each of the reservoirs may be maintained at a constant level, as will be well understood in the art. When the fuel in either of the reservoirs 90 falls below a predetermined level, the valve 8 will be lifted as the float descends, permitting the fuel to flow into the reservoir through the intake opening 7. As the float 95 is lifted by the inflowing fuel, the valve 8 will be seated to cut off a further inflow thereof.

Extending vertically of the body of the carbureter and located centrally therein is a circular partition 15 which connects the transverse partitions 2 and within which is formed the carbureting chamber 16, the lower end of which communicates with the air intake passage way 17 extending horizontally through the body of the carbureter. Crossing the inner end of the air intake and projecting vertically into the carbureting chamber is the fuel feed nozzle 18. In the upper end of said nozzle is rotatively seated the plug valve 19 whose stem 20 projects 100 from the lower end of said nozzle and carries the actuating handle 21. The valve 19

is held to its seat by packing 22 retained in place by a ring 23 embracing the stem of said valve and urged against said packing by a coiled spring 24 which also embraces said valve stem and is confined in the lower end of the nozzle by means of the threaded plug 25 screwed therein and through which the valve stem passes freely. Leading from the reservoir 4 and communicating with the upper end of the nozzle 18 is a fuel feed passage 26 through which the flow of fuel is controlled by a needle point valve 27 seated therein. The stem of said valve projects beyond the body and carries the knurled disk 28 for actuating it. The reservoir 3 also communicates with the upper end of said nozzle by means of the fuel feed passage 29 through which the flow of fuel is controlled by the needle point valve 30 seated therein, the outer end of the stem of said valve carrying the actuating disk 31. Formed in the upper end of the valve 19 is a passage 32 whose terminals open through the wall of said valve at right angles to each other, as is clearly shown in Figs. 6 and 7. Communicating with the angular passage 32 in said valve is a vertical passage 33. The upper end of the valve 19 is reduced, as shown at 34, and crossing said reduced portion is a transverse passage 35 with which the upper end of the vertical passage 33 communicates. Between the reduced upper end 34 of said valve and the wall of the nozzle at its upper end is an annular way 36 into which the opposite ends of the transverse passage 35 discharge, all of which is clearly shown in Fig. 3. By rotating the valve 19 through the medium of its handle, the terminals of the angular passage 32 therein may be caused to register successively with the fuel feed passages 26 and 29. When one of the terminals of said angular passage in the valve is made to register with one of the fuel feed passages, fuel from the reservoir with which said feed passage communicates will flow into said angular passage in the valve, thence through the vertical passage 33 into the transverse passage 35 and fill the annular space 36 at the upper end of the nozzle, being maintained therein at the level of the fuel in the reservoir with which the nozzle may be in communication, which level is normally slightly below the upper end of said nozzle. The fuel held in the end of the nozzle is drawn into the carbureting chamber by the inspirations of the engine and mixed with the air passing therethrough to form an explosive charge, as will be well understood.

It will be noted that the feed passages 26 and 29 communicate with the nozzle through opposite sides thereof, and that the shape of the angular passage 32 in the valve 19 is such that when one terminal of said passage is in communication with one of the

fuel feed passages, the other passage is closed by the wall of said valve, thereby insuring the feeding of fuel from but one reservoir at a time.

The reservoirs are closed by a cover 37 secured thereon having a central opening therethrough from which leads a hollow stem 38, the bore of which is of the diameter of the carbureting chamber, and which communicates therewith, said stem forming therethrough a mixture passage 39 which is connected in the usual way with the cylinder of an explosive engine. Within the mixture passage is a throttle valve 40 adapted to be actuated through the medium of a handle 80 or lever 41 on the end of the stem thereof.

It has been found by experiment that hydrocarbon oils of the density of kerosene, can be successfully used in internal combustion engines after the engine cylinder shall have become heated so as to heat said oil to such a degree as to render it sufficiently volatile to enable the commingling of air therewith to form an explosive mixture. The chief difficulty in using kerosene and oils of like density in explosive engines is the inability of starting the engine with such a fuel because of its low volatility under relatively low temperatures. It has been found that kerosene and like oils can be used successfully in connection with gasoline or volatile oils, by employing the volatile oil to effect a starting of the engine, and then, after sufficient heat has been generated to evaporate the kerosene, cutting off the supply of gasoline and feeding kerosene through the carburetor instead, the presence of heat expanding the particles of kerosene to form a gas which when mixed with the air passing through the carbureting chamber and through the heated induct chamber of the engine, produces a satisfactory explosive mixture which may be successfully employed to drive the engine. It will be understood that heat from the exhaust is employed in a manner not shown, to heat the induct pipe through which the explosive mixture is conveyed from the carburetor to the cylinder.

Because of the comparative cheapness of kerosene and analogous hydrocarbon oils and their relatively high heating qualities, a material saving is made by using kerosene instead of gasoline or the lighter volatile oils. It is important, however, that after running upon kerosene provision be made for leaving but a small quantity thereof in the fuel nozzle so that when it is desired to start the engine upon gasoline, it will not be necessary to work out of the nozzle by excessive cranking of the engine an undue amount of kerosene before the gasoline can be brought into use. To accomplish the above result, it will be noted that the fuel feed passages 26 and 29 lead to the

extreme upper end of the fuel nozzle and that the residuary fuel which can be left therein after an operation is only the comparatively small quantity which will lie in the passages in the upper end of the valve 19 and in the annular channel 36, which amount is insufficient to materially interfere with the starting of the engine.

In order to render practicable the operation of the engine upon two fuels of varying specific gravity, it is necessary to provide for the convenient supply of said fuels to a single nozzle in the carbureter so as to enable one to be turned off and the other turned on at will. Such provision I have made by feeding said fuels into the carbureter through a single valve, and forming said valve so that when it is actuated to permit the flow of one fuel into the feed 20 nozzle, the flow of the other fuel into said nozzle will be automatically cut off.

Having thus fully set forth my invention, what I claim as new and desire to secure by Letters Patent, is:—

25 1. In a carbureter, the combination of a casing having a plurality of independent reservoirs, a mixing chamber within the casing, a nozzle extending within the mix-

ing chamber, a plurality of independent conduits leading respectively from said reservoirs to adjacent the upper end of said nozzle, and a valve within the nozzle having a ported portion controlling said conduits and provided with an annular discharge opening.

2. In a carbureter the combination of a casing having a plurality of independent reservoirs, a mixing chamber within the casing, a nozzle extending within the mixing chamber, a plurality of independent conduits leading respectively from said reservoir to adjacent the upper end of said nozzle, a valve within said nozzle provided with a ported portion controlling said conduits, a vertical passage communicating with the ported portion and having a transverse passage communicating with said vertical passage, there being an annular discharge opening with which said transverse passage communicates.

In testimony whereof, I sign this specification in the presence of two witnesses.

GEORGE MELVIN HOLLEY.
